UNITED STATES PATENT OFFICE.

JOHN WILLIAM SMITH, OF SEWELLSVILLE, OHIO.

SIEVE.

SPECIFICATION forming part of Letters Patent No. 740,194, dated September 29, 1903.

Application filed March 24, 1903. Serial No. 149,376. (No model.)

To all whom it may concern:

Be it known that I, JOHN WILLIAM SMITH, a citizen of the United States, residing at Sewellsille, in the county of Belmont and State 5 of Ohio, have invented a new and useful Sieve, of which the following is a specification.

This invention relates to certain improvements in sifters, and more particularly to a reciprocating screen for sifting sand, coal, 10 ashes, and other material.

The object of the invention is to provide a simple, inexpensive, and efficient device of this character by means of which sand and other fine particles may be separated from 15 the gravel or coarser material.

A further object of the invention is to provide a reciprocating sieve the screen of which may be readily removed to facilitate the cleaning of the same or to permit the insertion of 20 screens of different mesh suitable to the character of the work to be performed.

A still further object is to pivotally connect the screen-box to the reciprocating carriage, so that when the screening operation is completed 25 the box may be tilted and discharge the remaining gravel or other coarse material preparatory to introducing a new charge.

The invention consists in the construction and novel combination and arrangement of 30 parts hereinafter fully described, illustrated in the accompanying drawings, and pointed out in the claims hereto appended, it being understood that various changes in form, proportions, and minor details of construction 35 may be resorted to without departing from the principle or sacrificing any of the advantages of this invention.

In the accompanying drawings, Figure 1 is a longitudinal sectional view of a sifter constructed 40 in accordance with my invention. Fig. 2 is a side elevation, partly in section, showing the arrangement of the sand-box. Fig. 3 is a transverse section of the same, and Fig. 4 is a detail perspective view of the 45 screen-box and screen detached.

Similar numerals of reference indicate corresponding parts in all the figures of the drawings.

1 designates a frame or casing formed of 50 wood or other suitable material, consisting of the side pieces 2, connected in any suitable

manner to the bottom 3 and provided with legs or supports 4. The bottom of the frame is provided with one or more openings 5, having chutes or deflector-plates 6 secured to the 55 side walls thereof and through which the sifted sand or other material is conveyed to suitable receptacles adapted to receive the same. Journaled in suitable bearings in the side pieces 2 and preferably at a point adjacent the end of the frame is a crank-shaft 7, having a balance-wheel 8 secured to one end thereof and having a pinion 9 at its opposite end, said pinion meshing with a master-gear 10, keyed to shaft 11, also journaled in the 65 side pieces 2 of the frame. The master-gear is provided with a suitable crank-handle 10', which may be used when the sieve is to be operated by hand; but this may be removed and the machine operated by a power-belt applied to a belt-wheel 11' on the main shaft 11. The shaft 7 is provided with a crank 12, to which is pivotally connected one end of a pitman 13, the opposite end thereof being pivotally connected to a reciprocating 70 carriage 14, mounted in guides 15, secured in any suitable manner to the side pieces of the frame. The carriage is in the form of an open rectangular frame and forms a support for a screen-box 16, connected at one end to 80 the carriage by a hinge or pivot 17 and provided at its opposite end with a means for interlocking with the carriage, a hook 18 and a keeper being shown in the present instance.

The screen-box is adapted to receive interchangeable sieves, which may be removed for repairs when damaged or for the substitution of screens of different mesh in accordance with the character of the work to be performed. Each screen 19 has a preferably rectangular supporting-frame 20, sliding in suitable guides 21, arranged within the box 16, the rear end of the screen fitting within a groove 22 in the rear end wall of the box, the front end of the screen-frame 95 being rabbeted, as shown, so as to lie flush with the front of the box, a button 23 being employed for locking the screen within the box.

Slidably mounted within the frame 1 and arranged beneath the screen is a drawer or receptacle 24, adapted to receive the sifted

sand or other material when it is inconvenient to convey the same through the openings 5 to separate receptacles.

In operation when it is desired to sieve 5 large quantities of sand or other material the drawer 24 is withdrawn from over the openings 5, or, if desired, it may be entirely removed. The sand is then introduced in the screen-box and by applying power to the 10 belt-wheel 11' or by turning the handle 10' the carriage carrying the sieve is reciprocated, the sifted material passing through the openings 5 and the gravel or coarse material remaining in the screen-box, which may after- 15 ward be tilted and discharged of its contents, as clearly shown in dotted lines in Fig. 2 of the drawings. When it is merely desired to sieve small quantities, the drawer is slid forwardly to a position directly beneath 20 the sieve and covering the openings in the bottom of the frame, the sifted material being deposited in the drawer when the machine is operated instead of passing through said openings. The screen may be readily 25 removed to facilitate the cleaning of the same or to permit the insertion of screens of different mesh by releasing the button 23, said screen being slidably and removably secured within the box, as before stated.

30 From the foregoing description it will be seen that I have provided an extremely sim-

ple and inexpensive sifter adapted to be operated by either hand or power which may be used for sifting sand and other materials and which will thoroughly and effectively 35 separate the fine particles from the gravel or coarser material.

Having thus described the invention, what I claim, and desire to secure by Letters Patent, is—

In a sifter, the combination with a frame, of a sand-receiving receptacle slidably and removably mounted within the frame, discharge-chutes arranged in the bottom of the frame, a reciprocating carriage supported by the frame 45 a screen-box pivoted to the carriage, guides within the box, a removable screen slidably mounted on said guides, one end of the screen fitting in a groove in the rear end of the screen-box, the opposite end of the screen 50 fitting in an opening in the front thereof, means for locking the screen in the screen-box, means for locking the screen-box to the carriage, and means for reciprocating the carriage.

In testimony that I claim the foregoing as my own I have hereto affixed my signature in the presence of two witnesses.

JOHN WILLIAM SMITH.

Witnesses:

R. T. BECK,
S. A. THOMPSON.
